LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed October 10, 1925. Serial No. 61,641.

This invention relates to compressor unloaders, but more particularly to an unloader of the step-by-step type in which the unloading is effected by the combined use of clearance chambers and inlet valves.

The objects of the invention are to produce a simple, cheap and efficient unloader for compressors in which a single clearance chamber is provided for each cylinder and a clearance valve for the tank together with the inlet valves at each end of the cylinder are automatically operated by a single regulator controlled by discharge or receiver pressure.

15 The unloader is applicable to single or double acting cylinders, also to duplex or compound compressors.

The invention is shown in one of its preferred forms in the accompanying drawings, 20 in which

Figure 1 is a diagrammatic side elevation partly in section and partly broken away showing the invention applied to a single or double acting cylinder, and

25 Figures 2, 3, 4 and 5 are similar views showing the different steps of unloading.

Referring to the drawings, the cylinder A is provided with a piston B, and the air drawn from the inlet C is discharged 30 through the discharge pipe D to the receiver E in the usual manner.

The cylinder is provided with the inlet valves F and G, which may be plate valves of any suitable type, each provided with 35 valve openers H and J of any suitable form, having the fingers K and L and the pistons O and P operating in the cylinders Q and R. These cylinders are preferably provided with the leak ports S and T to permit the pistons O and P to be quickly retracted by the springs U and V. The valves F and G are held open by receiver pressure supplied 40 through the pipes W and X respectively, and connected to the single regulator Y, to be described.

The discharge valves Z for the cylinder may be of any suitable type, shown in this 50 instance as plate valves. One end of the cylinder A is provided with the clearance chamber a having the clearance valve b provided with the piston c operating in the cylinder d and normally pressed to its seat e by the spring f. The cylinder d is preferably provided with the leak port g and another leak port h leads from the forward

end of the cylinder in front of the piston c. The clearance valve b is adapted to be opened and held open by receiver pressure supplied through the pipe j connected to the regulator Y. The pipe k connects the receiver E with the regulator, as shown. The regulator Y in this instance comprises a cylinder having a piston o which forms a valve and controls the ports p, q, r and s in the wall of the regulator cylinder. The pipe X is provided with branches t and u leading to the ports q and r. The piston valve o is actuated in one direction by receiver pressure and in the opposite direction by the spring v having the adjusting screw w. A leak port x is provided for that end of the regulator in which the spring is located. The piston valve o is conveniently provided with the passage y communicating with the spaced ports 2 and 3.

In the operation of the device let it be assumed that the clearance valve b is closed and that the inlet valve openers are retracted, so that the inlet valves are functioning normally. In such case the compressor will be under full load and the regulator is so constructed that the compressor is unloaded step by step, in accordance with the discharge pressure, that is, three-quarter load, one-half load, one-quarter load, and no load, permitting five steps of control from full load to no load, although the number of steps may be varied as desired.

In Figure 2 let it be assumed that the receiver pressure first actuates the piston valve o to bring the port 3 opposite the port p, in which case receiver pressure will be supplied to the clearance valve piston c causing the clearance valve to open and unloading the cylinder one-quarter, so that the cylinder is placed under three-quarter load. A further movement of the piston valve o to the left, as indicated in Figure 3, will bring the port 3 opposite the port q and will close the port p, so that receiver pressure is supplied to the valve opener of the inlet valve G at the end of the cylinder opposite the clearance chamber while at the same time the leakage of pressure fluid from the clearance valve cylinder to atmosphere through the leak port h will permit the clearance valve to close, thus placing the cylinder under half load. Further movement of the piston valve o to the left places the port 3 in communication with the

port r and places the port 2 in communication with the clearance valve port p so that the clearance valve b is again opened while the inlet valve G is maintained in open position so that the compressor operates under one-quarter load. The last and final movement of the piston valve o closes the clearance valve port p , which causes the clearance valve to close but brings the ports 2 and 3, respectively, opposite the ports q and s , thus causing the inlet valve F to open while maintaining the inlet valve G open and completely unloading the cylinder. The steps are repeated in reverse order as the cylinder is located.

I claim:

1. In a compressor unloader, the combination of a cylinder and piston, inlet and discharge valves, a clearance chamber for one end of the cylinder, a clearance valve for said chamber, and means for unloading the compressor in steps by first opening the clearance valve, then closing the clearance valve and holding an inlet valve open at the opposite end of the cylinder, then again opening the clearance valve while maintaining the said inlet valve open, and finally closing the clearance valve and opening the inlet valve at the clearance end of the cylinder while maintaining the inlet valve open at the opposite end of the cylinder.

2. In a compressor unloader, the combination of a cylinder and piston, inlet and discharge valves, a clearance chamber for one end of the cylinder, a clearance valve for said chamber, and automatic unloading devices responsive to the rise in discharge pressure for unloading the compressor step by step, by first opening the clearance valve, then closing the clearance valve and holding an inlet valve open at the opposite end of the cylinder, then again opening the clearance valve while maintaining the said inlet valve open, and finally closing the clear-

ance valve and opening the inlet valve at the clearance end of the cylinder while maintaining the inlet valve open at the opposite end of the cylinder.

3. In a compressor unloader, the combination of a cylinder and piston, inlet and discharge valves, a clearance chamber for said chamber, and a single automatic regulator responsive to the rise in discharge pressure for unloading the compressor step by step, by first opening the clearance valve, then closing the clearance valve and holding an inlet valve open at the opposite end of the cylinder, then again opening the clearance valve while maintaining the said inlet valve open, and finally closing the clearance valve and opening the inlet valve at the clearance end of the cylinder while maintaining the inlet valve open at the opposite end of the cylinder.

4. In a compressor unloader, the combination of a cylinder and piston, inlet and discharge valves, a clearance chamber for said chamber, and a single automatic regulator responsive to the rise in discharge pressure for unloading the compressor step by step, by first opening the clearance valve, then closing the clearance valve and holding an inlet valve open at the opposite end of the cylinder, then again opening the clearance valve while maintaining the said inlet valve open, and finally closing the clearance valve and opening the inlet valve at the clearance end of the cylinder while maintaining the inlet valve open at the opposite end of the cylinder, said regulator comprising a pressure fluid actuated movable member, and a plurality of pressure fluid connections to the clearance valve and inlet valves controlled by said member for carrying out the said cycle.

In testimony whereof I have signed this specification.

LEWIS C. BAYLES.
